UNITED STATES PATENT OFFICE.

HANS J. NIELSEN, OF MAYER, ARIZONA.

KEY-GUARD.

1,368,743.

Specification of Letters Patent. Patented Feb. 15, 1921.

Application filed November 30, 1917. Serial No. 204,542.

To all whom it may concern:

Be it known that I, HANS J. NIELSEN, citizen of the United States, residing at Mayer, in the county of Yavapai and State of Arizona, have invented certain new and useful Improvements in Key-Guards, of which the following is a specification.

This invention is an improved device for preventing keys from being inadvertently carried away by guests or patrons of a public house or institution.

The invention has for its object the provision of a device similar to those now in use, but one which will be readily convertible into a different position at the will of the owner or custodian of the key to be protected, in which position it will assume an irregular or unwieldy shape which will materially lessen the possibility of its being carried away by absentminded persons using said key.

The invention will be hereinafter fully set forth and particularly pointed out in the claims.

25 In the accompanying drawing:—

Figure 1 is a front view of my improved device. Fig. 2 is a vertical central section of same. Fig. 3 is a side view in a possible position. Fig. 4 is a perspective view in the position shown in Fig. 3. Fig. 5 is a fragmentary view of a modified detail. Fig. 6 is a view similar to Fig. 5 with the parts thereof in another position.

Fig. 7 is a sectional view taken on line 35 7—7 of Fig. 5.

Fig. 8 is a view of the key for unlocking the lock of the modified form of my invention shown in Figs. 5 and 6.

Fig. 9 is a view showing the latch, spring 40 and key of the lock of my invention shown in Figs. 1 to 4 inclusive.

Fig. 10 is a sectional view taken on line 10—10 of Fig. 1.

Referring to the drawing, 10 indicates an 45 appendage or reminder to be attached to a key. Obviously this may be of any shape, but in this case that of a star is chosen because of the irregularity of its outer edge. At its uppermost point the reminder 1 is 50 provided with a ring 2 having a central hole 3^a adapted to engage a link or chain attached to a key. The reminder 1 is composed of two members 3 and 4 hinged together as shown at 6. The member 3 is similar in form to the member 4 except that it

has no ring attached, and its lower portion below the hinge is cut away to allow it to move outwardly and downwardly to the position shown in Figs. 3 and 4. Said member 3 has in place of the ring at its uppermost 60 extremity, an outturned point, as shown at 5, to facilitate the opening or spreading of the members 3 and 4.

The member 3 has on its outer surface a lock 7, opposite a keyhole 8, in which is a 65 post 9, on which is slidable vertically a latch 10, having a vertical slot 11. The latch is actuated by one end of a spring 12, secured to the side wall of the lock, said end bearing against the top of the latch 10. The 70 opposite end 15, of said spring is bent inwardly from the wall of the lock and adapted to engage a notch 13 in the latch. The latch 10 is bent at its lower end forming a short transverse member 14, substantially 75 at right angles to the vertical portion. The said transverse member 14 is engaged in a slot 16 in the member 4.

In the normal position of the reminder (see Fig. 1) it will be seen that the pressure of the spring is against the upper end 80 of the latch, the downward motion being arrested by the transverse member of the latch which bears against the lower edge of the slot 16. When the reminder is opened and 85 the member 3 assumes a position at right angles to the member 4 the pressure of the spring upon the latch forces said latch through the slot 16, because of the fact that the transverse member of said latch is now 90 in a position which offers no resistance to the spring. It will be readily seen that by this arrangement, the device will be held in a substantially rigid position because of the contact of the edge of the lock (as shown 95 at 17, Fig. 3) with the surface of the member 4, while the lower surface of the latch bears against the lower edge of the slot 16.

The device is held by these opposed impediments and locked by the engagement of 100 the notch 13 with the end of spring 15. It will require a key in the possession of the custodian to release the lock and restore the device to its normal or closed position for storage.

In the modification shown in Figs. 5 and 6, a latch of a different construction is used and the slot 16 in the former figures is dispensed with. In said Figs. 5 and 6, 10^a indicates a modified latch having a reduced por- 110

tion 18, surrounding which is coiled spring 19, the one end of which bears against the upper wall of the lock and the opposite end against the shoulder formed by the reduced member 18. The opposite end of said latch 10^a, is rounded as shown at 20, to facilitate its entry into a recess 21, punched or stamped into the member 4 of the reminder. This construction avoids the possibility of the latch being broken or interfered with from the rear.

On the latch 10 is a pin 30. A key 31 has two diametrically opposed lugs 32 and 33. The end of the key is recessed to fit on the post 9 and the lugs 32 and 33 respectively engage spring 15 and pin 30, when the key is turned, to disengage spring 15 from latch notch 13 and to withdraw the latch inwardly through slot 16 to unlock the device so that the members 3 and 4 may be closed.

The engaging end of the latch 10^a is reduced, forming shoulders 40 for engaging lugs 41 on the lock casing to limit the outward movement of the latch. The lock has a key post 42 extending into a recess 43 in the latch 10^a, a shoulder 44 being formed at one side of the recess to be engaged by the key 45 to withdraw the latch from recess 21 to unlock the device. The lock casing has a keyhole 46 through which the key is inserted into the lock.

Having thus explained the nature of the invention, and described an operative manner of constructing and using the same, although without attempting to set forth all of the forms in which it may be made, or all of the forms of its use, the following is claimed:—

1. An attachment for keys comprising two sections having a hinged connection, one of the sections being provided with means whereby it may be attached to the

key, and means for locking said sections in angular relation.

2. An attachment for keys comprising two sections having a hinged connection, one of the sections being provided with means whereby it may be attached to a key, and a spring pressed bolt carried by one section, the other section having a complementary portion to receive said bolt to lock said sections in angular relation.

3. An attachment for keys comprising two sections having a hinged connection, one of the sections being provided with means whereby it may be attached to a key, a slideable bolt carried by one of said sections, the other sections having a complementary portion to receive said bolt for locking said sections in angular relation, and means for normally preventing movement of said bolt.

4. An attachment for keys comprising two sections having a hinged connection, one of the sections being provided with means whereby it may be attached to a key, said section being provided with a slot, and a slideable bolt carried by the other section and provided with an offset portion projecting through said slot for locking the sections in angular relation.

5. An attachment for keys comprising two sections having a hinged connection, one of the sections being provided with means whereby it may be attached to a key, a slideable bolt carried by the other section, said bolt having a notch, the first mentioned section having a complementary portion to receive said bolt for locking the sections in angular relation, and a spring acting to move said bolt and having an arm to engage said notch.

In testimony whereof I affix my signature.
HANS J. NIELSEN.
